UNITED STATES PATENT OFFICE.

HENRY RUSH, OF SEDAN, KANSAS.

GAS-WELL VALVE STRUCTURE.

Application filed February 7, 1924. Serial No. 691,261.

To all whom it may concern:

Be it known that I, HENRY RUSH, a citizen of the United States, residing at Sedan, in the county of Chautauqua and State of Kansas, have invented certain new and useful Improvements in Gas-Well Valve Structures, of which the following is a specification, reference being had to the accompanying drawings.

10 This invention relates to a valve structure for use in gas wells and one object of the invention is to provide a valve structure which may be used in connection with a gas well and will serve to cause water which normally accumulates in the bottom of the gas well to be forced upwardly and out of the well. At the present time no means is provided for removing water from a gas well except by what is known as blowing the well. When a gas well is blown, and under present conditions this is necessary every few days, a large quantity of gas escapes but with the use of this improved device the blowing of the well is not necessary and 25 therefore the gas, which, at the present time, is lost during the blowing operation, is saved.

This invention is illustrated in the accompanying drawings, wherein:—

Figure 1 is a longitudinal sectional view 30 through a portion of a gas well showing the improved valves in use.

Figure 2 is a longitudinal sectional view through one of the valves.

Figure 3 is a transverse sectional view 35 taken along line 3—3 of Figure 2.

This improved valve structure is for use in connection with a gas well which will be provided with the usual casing 1 and tube 2 which extends downwardly through the casing 1 in spaced relation to the walls of the casing. At the lower end of the tube there has been provided a packer 3 which will be firmly held in place and have tight engagement with the walls of the tube so 45 that gas and water passing upwardly through the tube must pass through this hollow packer. A pipe 4 extends downwardly through this inner tube and is provided with lower sections 5 and 6, the section 5 being connected with the main body of the pipe 4 by a valve housing 7 and with the lower section 6 by means of a valve housing 8. The lower section 6 has its lower end connected with a valve housing 9 which 55 rests upon the packer 3 and has close fitting

engagement with the upper end of the packer. It will thus be seen that the gas and water must pass upwardly through the lower sections 5 and 6 and valve housings in order to reach the outlet pipe 4. The valve 60 housings are of a similar construction and each is provided with a cylindrical body having its lower end portion internally thickened as shown at 10 to provide a reduced passage and a concaved valve seat 11 65 at the upper end of the thickened portion. A ball valve 12 is placed in the body for normally seating upon the valve seat 11 and preventing gas and water from passing downwardly through the passage in the lower 70 end portion of the valve body. Upward pressure will raise the valve ball so that the gas and water may pass upwardly but when the pressure decreases the valve ball will seat upon the valve seat and prevent downward movement of the gas and water. A pin 13 extends transversely through the valve body above the valve ball so that upward movement of the valve ball is limited.

When this device is in use the pipe 4, 75 having the lower sections 5 and 6 and valve members 7, 8 and 9 connected therewith, is lowered in the inner tube of the gas well until the lower valve casing 9 rests upon and forms a tight joint with the packer 3. 80 The distance from the upper end of the packer to the valve seat 11 of the lower valve member 9 will be approximately twenty-five feet, the distance from the valve seat of the lower valve member to the valve 85 seat of the second valve member 8, approximately one hundred and fifty (150) feet, and the distance from the valve seat 11 of the second valve 8 to the valve seat of the upper valve member 7, approximately two 90 hundred (200) feet. The distance between the lower valve member and the intermediate valve member 8 and the distance between the intermediate valve member and the upper valve member may, however, be 95 varied by simply providing pipe sections 5 and 6 of different lengths, if it is found necessary, in order to produce a better working device when in use. As the water tends to accumulate in the bottom of the gas well the pressure of the gas will force this water upwardly through the inner pipe and valves associated therewith and as this water must pass through the valves as it moves upwardly through the pipe, it will 100 105 110

be prevented from returning to the bottom of the well. Therefore, the water will be gradually lifted in the pipe 4 until it reaches such a height that it can be drawn off through the medium of a drip system. It will thus be seen that by means of this arrangement of valves the gas well, even though the water accumulates rapidly, may be kept free of water and no gas is lost by 10 a blowing operation.

What is claimed is:—

1. In a gas well, a casing, a tubing therein spaced from the walls thereof, a tubular packer fitting snugly within the tubing, an 15 outlet pipe including a plurality of sections, valve casings connecting the successive sections, the valve casings and outlet pipe sections being spaced from the wall of the tubing, and the lowermost valve casing 20 seating upon said packer, each valve casing being formed internally with a shoulder de-

fining a valve seat, and an upwardly opening valve upon each seat.

2. In a well, a casing, a tubing therein spaced therefrom, a resilient tubular packer 25 within and fitting snugly against the tubing, an outlet pipe spaced from the wall of the tubing and formed of a plurality of sections, a plurality of cylindrical valve casings secured onto the adjacent ends of the 30 pipe sections, a similar valve casing at the lower end of the lowermost section fitting upon the upper end of the packer, each valve casing being formed internally with a valve seat, a ball valve within each casing 35 normally resting upon the seat, and means within each casing for preventing engagement of the ball valve with the lower end of the pipe section.

In testimony whereof I hereunto affix my 40 signature.

HENRY RUSH.
